UNITED STATES PATENT OFFICE

2,620,531

PLASTERBOARD LATH CLIP FOR METAL
STUDDING

Franklin R. Chandler, San Diego, Calif.

Application October 21, 1950, Serial No. 191,413

5 Claims. (Cl. 24—81)

1

My invention relates to plasterboard lath clips for metal studding, and the objects of my invention are:

First, to provide a lath clip of this class which is provided with a straddling portion adapted to straddle one leg of metal studding and the web structure thereof, whereby edges of plasterboard lath panels may be disposed in abutting relationship to each other at or near the juncture of the web structure of the metal studding with the legs thereof;

Second, to provide a lath clip of this class in which the straddling portion thereof, in engagement with metal studding, is extended longitudinally of the studding around the juncture of the internal structure of the studding with the outer legs thereof, whereby the clip may be located in any position longitudinally of the metal studding, as desired;

Third, to provide a lath clip of this class which is very simple and easy to install in connection with metal studding and plasterboard lath;

Fourth, to provide a lath clip of this class which may be located longitudinally in any position desired on various metal studding structures;

Fifth, to provide a lath clip for metal studding which may be readily and easily employed as a base or finish clip at the lower and upper portions of a lath wall structure, respectively; and

Sixth, to provide a plasterboard lath clip for metal studding which is very simple and economical of construction, efficient in operation, and which will not readily deteriorate or get out of order.

With these and other objects in view, as will appear hereinafter, my invention consists of certain novel features of construction, combination and arrangement of parts and portions, as will be hereinafter described in detail and particularly set forth in the appended claims, reference being had to the accompanying drawings and to the characters of reference thereon, forming a part of this application, in which:

Fig. 1 is a side elevational view of one of my plasterboard lath clips for metal studding, showing by dash lines a conventional metal studding and plasterboard lath supported thereon by said clip; Fig. 2 is a front elevational view of my plasterboard clip for metal studding, taken substantially ninety degrees to that shown in Fig. 1 of the drawing; Fig. 3 is a perspective view of my plasterboard lath clip for metal studding; Fig. 4 is a similar view to Fig. 1, showing my plasterboard lath clip for metal studding used as a base fitting after a clip portion thereof has been

5

snipped off; and Fig. 5 is a side elevational view of the structure shown in Fig. 4 of the drawings.

Similar characters of reference refer to similar parts and portions throughout the several views of the drawings.

The conventional metal studding, as shown in Figs. 1 and 4 of the drawings, is provided with spaced legs A and B, which are normally parallel to each other, and interconnecting these spaced legs A and B is a conventional brace or web structure, according to the particular construction of the particular metal studding. Several different types of metal studding on the market may be accommodated by my plasterboard lath clip for metal studding, some of which is of pressed steel and some of which is substantially as shown, made of round bars welded together. Conventional plasterboard lath clips for metal studding are not easily installed at the juncture 10 of the legs A and B with the brace or web structure C, and sometimes prevent the lather from fitting the plasterboard panels D in abutted relationship to each other at their edges, all of which cause greater labor costs and difficulty in plastering.

My plasterboard lath clip for metal studding is provided with an offset straddling portion 1, which is U-shaped and which extends around the juncture portions of the web or brace structure C with the leg structures A or B. The U-shaped straddling portion 1 is provided with central portion 1p and opposed legs 1a and 1b having integral offset portions 1c and 1d, respectively, disposed at right angles thereto, with which the clips 1e and 1f, respectively, are integral. In Figure 3 it will be noted that continuous with offset portions 1d and 1c are inside middle portions 1m and 1n of clips 1f and 1e respectively. These inside middle portions are parallelly aligned relative to each other. The outside middle portions 1k and 1g are also parallel relative to each other. These clips 1e and 1f are adapted to engage conventional plasterboard lath above and below the offset portions 1c and 1d, and the lath engaged by the clips 1e and 1f are contiguous to the offset portions 1c and 1d, as shown best in Fig. 1 of the drawings. The clip portions 1e and 1f are also provided with leg portions 1j and 1h, which cooperate with inside and outside middle portions 1k and 1m, and 1g and 1n, respectively, to engage inner and outer sides of the plasterboard lath for holding the same in alignment and securely connected to the conventional metal studding.

As shown in Fig. 5 of the drawings, the clip portion 1e is snipped off at the end of the offset

55

portion *1c*, providing a base clip for the lowermost edge of the lowermost plasterboard lath of a wall. The clip may be altered in a similar manner for the upper finishing edge of the lath, as desired.

The operation of my plasterboard lath clip for metal studding is substantially as follows:

Said clip, altered as hereinbefore described, may be placed for supporting the edge of the plasterboard *D* adjacent the conventional base, and the U-shaped straddling portion *1* not only straddles the leg *B* but also the brace or web structure *C*, permitting the lather to make the desired vertical adjustment necessary. In the event it is desired to place the enclosed end or central portion *1p* of the straddle portion *1* of the clip below the brace or web structure *C*, the clip *1f* is snipped off at its juncture with the portion *1d*, permitting the U-shaped straddling portion *1* to be installed below said web or brace structure *C* at its closed portion. When the first plasterboard lath panel has been installed and extends upwardly from the base, the clip, as shown in Fig. 3 of the drawings, is placed in straddling relationship with the leg *B* of the metal studding at the straddle portion *1* of said clip, and the clip *1e* is placed over the outer and inner sides of the lath *D*, which supports the upper edge thereof securely while the next superimposed lath panel is installed.

It will be noted that the length of the U-shaped straddle portion *1* permits the lather to slide the clip vertically in either direction about the area of the transition of the brace or web *C* with the vertical leg *B* of the metal studding. Thus, adjacent edges of successive superimposed lath panels *D* may be very close to each other, as shown in Fig. 1 of the drawings.

It will be further noted that the installation of my plasterboard lath clip for metal studding is very simple, inasmuch as the clip may be positioned in straddling relationship with the leg *B* of the metal studding and vertically slidably adjusted without the necessity of inserting any portion of the clip through brace or web structure in the metal studding.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In a plasterboard lath clip for metal studding, a single piece wire member comprising opposed U-shaped clip portions having inside middle portions in parallel alignment with each other engaging adjacent edges of plasterboard lath, said opposed clip portions having an interconnecting integral offset U-shaped studding leg straddling portion spaced from and disposed substantially parallel to the plane of lath engaged by said clip portions, said U-shaped studding leg straddling portion having a central portion spaced vertically from the middle portions of said U-shaped clip portions, whereby said U-shaped straddling portion is adapted to be longitudinally slidably adjusted over web or brace structure at its transition with the legs of metal studding.

2. In a clip of the class described, a single piece wire member comprising a U-shaped strad-

dling portion disposed on the inner side of a conventional metal studding leg, and extending around the transition of said leg with a conventional web or brace structure of the metal studding, said U-shaped straddling portion having integral offset portions provided with clips extending in opposite directions from said offset portions and engaging adjacent edge portions of conventional plasterboard lath panels, said opposed clip portions having inside and outside middle portions and integral legs engageable with opposite sides of said plasterboard lath panels, and the plane of said U-shaped straddling portion vertically spaced from the plane of the middle portions of said clips.

3. In a clip of the class described, a single piece wire member comprising a U-shaped straddling portion disposed on the inner side of a conventional metal studding leg, and extending around the transition of said leg with a conventional web or brace structure of the metal studding, said U-shaped straddling portion having integral offset portions provided with clips extending in opposite directions from said offset portions and engaging adjacent edge portions of conventional plasterboard lath panels, said opposed clip portions having inside and outside middle portions and integral legs engageable with opposite sides of said plasterboard lath panels, the plane of said U-shaped straddling portion vertically spaced from the plane of the middle portions of said clips and adapted to hold the plasterboard panels in alignment and connected to said metal studding.

4. A single piece wire member comprising a pair of clip portions having opposed extending portions for engaging adjacent edges of a pair of plasterboard lath panels, each of said clips being provided with middle portions horizontally aligned with each other, U-shaped straddling means integral with said clips, and said straddling means having horizontally aligned opposed legs vertically spaced relative to the middle portions of said clips engageable with the rear side of a conventional metal studding leg and extending around opposite sides of a web or brace structure at its transition with said leg.

5. A single piece wire member comprising a pair of clip portions having opposed extending portions for engaging adjacent edges of a pair of plasterboard lath panels, each of said clips being provided with middle portions horizontally aligned with each other, U-shaped straddling means integral with said clips, said straddling means having horizontally aligned opposed legs vertically spaced relative to the middle portions of said clips engageable with the rear side of a conventional metal studding leg and extending around opposite sides of a web or brace structure at its transition with said leg, and said straddling means extending a considerable distance longitudinally of the leg of a studding structure on which it is engaged.
